UNITED STATES PATENT OFFICE

JOSEPH GALAMB, OF DETROIT, MICHIGAN, ASSIGNOR TO FORD MOTOR COMPANY, OF DEARBORN, MICHIGAN, A CORPORATION OF DELAWARE

DOOR LATCH

Original application filed August 15, 1927, Serial No. 212,909. Divided and this application filed August 31, 1929. Serial No. 389,657.

The object of my invention is to provide a door latch of simple, durable and inexpensive construction.

Still a further object of my invention is to provide a door latch specially adapted for use in connection with the doors of an automotive vehicle whereby the door pillars may be of a minimum thickness to thereby make the vision from the body greater and whereby the controls for opening the latch may be very conveniently placed.

Still a further object of my invention is to provide a door latch for an automobile body door wherein the door is made from sheet metal and comprises inner and outer panels with the door pillars therebetween whereby the glass channel for the door may rest against the inner surfaces of the door pillar thereby largely decreasing the cross section of the door pillar.

Still a further object of my invention is to provide a door latch wherein the outside door handle may be disposed adjacent to the surface of the door glass and the inside door handle may be disposed at a place spaced very materially from the door pillar and the door latch may be shaped to pass around the edge of the door glass to thereby make the latch construction compact and so that it will not materially increase the cross sectional area of the door pillar.

Still a further object of my invention is to provide a door latch for use in connection with a sheet metal door wherein the latch is formed from a strip of sheet metal which is bent angularly at various points along its length to provide a bridge extending around the edge of the door glass and a lug at either end which may be operated by the adjacent door handle whereby the door latch may be operated from either the inside or the outside of the door, and still it is not necessary to run any parts of the lock directly through the door pillar to thereby increase the necessary cross sectional area of said pillar.

Still a further object of my invention is to provide means which will not materially increase the cross sectional area of the door pillar and which may extend across the outer surfaces of the door pillar to latch the out-

side door handle so that it may not be operated from the outside of the car.

Still a further object of my invention is to provide in combination with such a latch, an inside door handle, which may be extended to position near the center of the door or to whatever position may be most convenient for the operator to reach.

With these and other objects in view my invention consists in the arrangement, combination, and construction of the various parts of my improved device as described in the specifications, claimed in the claims and illustrated in the accompanying drawings in which:

Figure 1 shows an elevation of my improved door latch looking along the inside of the door toward the door pillar, the glass channel and glass being removed in order to better illustrate the construction.

Figure 2 shows a horizontal sectional view through the door and body pillar taken on the line 2—2 of Figure 1, the inside operating handle being shown to better illustrate the construction.

Figure 3 shows a vertical sectional view taken on the line 3—3 of Figure 1.

Figure 4 shows a vertical sectional view taken on the line 4—4 of Figure 1.

Figure 5 shows a portion of the inside door panel, the upholstery being removed to better illustrate the construction.

Figure 6 shows a vertical sectional view taken on the line 6—6 of Figure 2.

Figure 7 shows a vertical sectional view through the inside door panel adjacent to the place where the inside door handle extends therefrom to thereby illustrate the position and mounting of said handle.

Referring to the accompanying drawings I have used the reference numeral 10 to indicate the outside door panel and reference numeral 11 to indicate the inside door panel. These parts are connected at the free edge of the door by the door pillar 12. This door pillar 12 is recessed near the central part thereof to receive a latch plate 13 which is suitably secured to the pillar 12 by rivets 14. This latch plate is provided with a recess within the central upper portion there-

of through which the door latch 15 may extend. It will be noted that this door latch 15 is formed from a single strip of sheet metal which has its central portion bent upon itself 5 to form an angular latch portion having a pocket or recess on the under side thereof and at the outer end of the latch portion, the strip is bent to form the lug 16. At the inner end of the latch portion proper, of the latch member 15, ears 17 are turned over and provided with aligned openings through which the latch pintle 18 may extend. This latch pintle 18 is fixed in spaced ears 19 which are struck inwardly from the material of the latch plate 13. It will be noted that a portion of the material which is cut out from the latch plate 13 to permit the latch 15 to pass therethrough may be turned up to form these ears 19.

20 At the outer edge of the latch plate 13 an integral tongue 20 is formed which extends perpendicular to the edge of the latch plate 13 and in substantially horizontal alignment with the latch 15. This tongue 20 forms one 25 of the brackets in which the rollback 21 is journaled, the latter being operated by the outside door handle and operating the outer end of the door latch 15. This rollback 21 is provided with an upwardly extending lug 22 which coacts with the lug 16 of the latch 15, so that the turning of the rollback 21 will move the lug 22 to thereby retract the latch 15. A second bracket 23 forms the journal for the free end of the rollback 21 and is secured 30 to the latch plate 13 by means of a turned-in foot 24. This bracket 23 has a portion which is bent upon itself as at 25 to form a door handle retaining member. This door handle retaining member has a square opening 26 therethrough for a purpose which will 35 hereinafter be described. A spring 27, having a couple of convolutions around the rollback 21, has one end thereof designed to coact with the surface of the latch plate 13 and the opposite end thereof bearing against the lug 22 on the rollback 21 (as will be seen in Figure 3) whereby the intermediate convolutions of this spring 27 may tend to move the rollback 21 to its normal as distinguished 40 from its retracted position. The rollback 21 has a squared opening therethrough designed to receive a square shank 28 on the outside door handle. This shank 28 is provided with an annular channel 29 adjacent to its inner 45 end whereby the squared end of the shank 28 may pass through the squared opening 26 in the retaining member 25 only when the door shank is in its operative position. The normal position of the outside handle when 50 the latch is in normal position is such that the shank will have to be rotated through approximately 45° from normal in order to reach the position in which it can pass through the squared opening 26. This therefore means that the outside door handle can-

not be withdrawn from the retaining member 25 when the latch is in normal position.

The outside door panel 10 is provided with an opening through which the shank 28 may pass. A washer 31 is disposed on the outside 70 of the outside door panel 10 around the shank 28 which is formed integral with an outside door handle 34.

An escutcheon plate 35 is rotatably but non-slidably mounted on the door handle 75 34, and is removably secured to the outside door panel 10 by screws 36, whereby said plate may normally support the door handle assembly on the door.

The washer 31 is rotatably but non-slidably 80 mounted on the door handle within the escutcheon plate 35 by means of a washer 66 and pin 67 whereby the door handle assembly may be removed or installed by turning the handle 45° and setting or taking out 85 two screws (36).

A spring 37 has a couple of convolutions 90 passing around the latch pintle 18 and one end thereof bearing against an extension 38 to the latch 15 while the opposite end of the spring bears against the inside door panel 11 at 39. This spring 37 therefore tends to normally urge the latch 15 into its normal or extended position. It will be noted therefore that the latch 15 may move to its retracted position when the door is closed without affecting the position of the outside door handle as the lug 16 simply moves away from the lug 22 and the latch will be returned to its normal position by spring 37. The latch 15 is provided beyond the extension 38 with the lug 40 which is formed integral therewith.

The inside door panel 11 is provided with a bead or channel 41 which coacts with clips 42 to provide a bearing for a rod 43 which extends along the outside of the inside door panel to operate the door latch from the inside of the door. The end of this rod 43 adjacent to the lug 40 is bent to form a crank 44 whereby rotation of the rod 43 may swing the crank 44 against the lug 40 to thereby retract the latch 15. The remote end of the rod 44 is provided with an arm 45 which is preferably formed integral therewith and which extends through a slot in the adjacent clip 42 so that a handle 46 may be secured thereto. It will be seen that if the handle 46 is grasped adjacent to its free end, pulling thereon away from the outer panel 11 will rotate rod 43 to thereby retract latch 15. It will be noted that this rod 43 may be of any suitable length so that the handle 46 may be placed at the most convenient place for the operator of the car to reach. A spring 47 is designed to coact with the rod 43 to return to the normal position with the arm 45 stopped against a stop 72 formed integral with the clip 42 and to prevent rattle thereof.

It will be noted that key operated locking means are ordinarily only provided in connection with one outside door handle in the ordinary automobile body and that the door latches are provided with an auxiliary locking means which may be operated from the inside in connection with the locks for the remaining doors so that they may not be opened by unauthorized persons from the outside.

10 Such a means is provided with my improved door latch and comprises a pair of clips 48 which are riveted to the inner door panel 11 to provide a sliding bearing for a bolt 49. This bolt 49 is provided with an operating handle 50 which is secured to the bolt 49 and extends through appropriate slots 51 in the clips 48 and the door panel 11 to permit the handle 50 to be reciprocated to reciprocate bolt 49. A second bolt 52 is 15 mounted on the latch plate 13 for reciprocation in a groove 53 in the plate 13. This bolt 52 is bent upon itself intermediate of its ends to form a stop member 68 designed when the bolt is in its extended position to 20 form a stop for a downwardly extending lug 55 on the dog 21. It will thus be seen that when bolt 52 is in its extended position the stop portion 68 of said bolt will extend between the lug 55 and the latch plate 13 to 25 prevent rotation of the rollback 21. Hence the outside door handle cannot be used to retract the latch 15 when the bolt 52 is in its extended position. A retaining clip 54 is 30 suitably secured to the inside of plate 13 to slidably secure bolt 52 in the groove 53. Movement of the bolt 49 parallel with the surface of door panel 11 is transmitted into 35 movement of the bolt 52 along the face of the latch plate 13 by means of the inclined ends of said bolts as is illustrated at 56 in Figure 4.

40 A coil spring 69 has one end engaged in a slot in a stud 70, which extends from the latch plate 13, and the other end bearing 45 against the stop member 68 of the bolt 52, to thereby normally urge the bolt 52 to retracted position. An offset 71 is provided in the bolt 52 to co-act with the inclined end of bolt 49 to resist the action of the spring 69 when 50 the bolts 49 and 52 are in extended or operative position. Movement of the stop 68 is entirely manually controlled from the handle 50. The spring 69 prevents rattle of the parts in their retracted position and 55 resiliently holds the bolt 49 in its forward or engaged position thru the offset 71.

60 Referring to Figure 4 it will also be noted that glass channel 57 which is normally disposed adjacent to a door pillar 12 contains a felt channel 58 in which a glass 59 may slide. Referring to Figure 2 it will be noted that this channel 57 extends to position contiguous to the door pillar 12.

65 Door latch 15 coacts with an adjustable striker plate 62 which is moved to the desired

position within a channel 63 which forms a part of the body pillar 64. Adjustment of the striker plate 62 is accomplished by loosening screw 65 to thereby permit the striker plate 62 to slide along the channel 63 to position to latch the door so that it will not rattle. Tightening screw 65 will then lock the striker plate due to the serrations on the bottom of the plate and the channel 63.

70 Among the many advantages arising from my improved latch it will be seen that I have provided means whereby the glass channel may rest against the central portion of the door pillar so that the total "blind spot" may be as small as possible.

75 Still a further advantage results from the use of my improved device in that separate spring means are provided for returning practically all of the parts to normal position so that rattle is largely eliminated.

80 Still a further advantage results from providing means for mounting the inside door handle whereby it may be extended to the position most convenient for the operator, and whereby the extended inside door handle may be mounted on the door with few additional parts and little change in the panel.

85 Still a further advantage results from the use of my improved latch device for the prevention of opening doors from the outside, as this does not materially add to the thickness of the door pillar.

90 Some changes may be made in the construction and combination and arrangement of my improved device without departing from the spirit of my invention, and it is my intention to cover by my claims such changes as may reasonably be included within the scope thereof.

95 This application is a division of my pending application Serial Number 212,909, filed 100 August 15, 1927.

105 I claim as my invention:

110 1. In a door latch, a door formed of sheet material having inside and outside panels connected at one edge by a door pillar, a latch mounted on the pillar, an outside door handle arranged to operate said latch, a bolt slidably mounted on the door pillar, and a second bolt slidably mounted on the inside panel in position so that operation thereof will operate the first mentioned bolt to position where the handle will not operate the latch.

115 2. In a door latch, a door formed of sheet material having inside and outside door panels connected at one edge by a door pillar, a latch pivotally mounted on said pillar an outside handle arranged to operate said latch, a horizontal bolt slidably mounted on the pillar, a second horizontal bolt slidably mounted on the inside panel, and means operated by the first mentioned bolt and co-acting with the outside handle so that when the second mentioned bolt is in its engaged position said 120

means will prevent the outside handle from operating the latch.

3. In a door latch, a door formed from sheet material having inside and outside door panels connected at one edge by a door pillar, a latch plate secured to said pillar having a latch pivotally mounted therein, a member pivotally mounted on said latch plate having an arm formed thereon in position to operate said latch, an outside door handle arranged to oscillate said member, a horizontal bolt slidably mounted on the latch plate having a stop formed thereon in position to coact with a second arm on said member, a second horizontal bolt slidably mounted on the inside door panel, co-acting with the first mentioned bolt so that when it is in its engaged position said stop will co-act with the second mentioned arm to prevent operation of the latch by the outside door handle.
4. In a door latch, a door formed from sheet material having inside and outside panels connected at one edge by a door pillar, a latch plate secured to said pillar, a latch pivotally mounted on said latch plate, an outside door handle arranged to operate said latch, a horizontal bolt slidably mounted on said latch plate arranged to operatively prevent rotation of said handle, a second horizontal bolt slidably mounted on the inside door panel, and an inclined surface on one of said bolts in position so that reciprocation of the second mentioned bolt will reciprocate the other bolt to prevent operation of the latch by the outside door handle.

5. In a door latch, a door formed from sheet material having inside and outside panels connected at one edge with a door pillar, a latch mounted in said pillar, an outside handle arranged to operate said latch, a bolt slidably mounted in said pillar, a second bolt slidably mounted on the inside panel, and inclined co-acting surfaces on the adjacent ends of said bolts in position so that reciprocation of the last mentioned bolt will operate the first mentioned bolt to prevent operation of said latch by the door handle.

6. In a door latch, a door formed from sheet material having inside and outside panels connected at one edge by a door pillar, a latch mounted on said pillar, an outside operating handle for said latch, a horizontal bolt slidably mounted on said pillar, a stop arranged on said bolt for operatively preventing the operation of said latch by the door handle, a spring arranged to resiliently urge the bolt to its inoperative position, a second bolt slidably mounted on the inside door panel, co-acting inclined surfaces on said bolts, and frictional locking means operated by said spring arranged so that the second mentioned bolt will be resiliently held in its engaged position.

JOSEPH GALAMB.
